Primary Examiner — Catherine Ho*Assistant Examiner* — Natalya M Rapundalo(74) *Attorney, Agent, or Firm* — Kunzler Bean & Adamson, PC; Alandra Adams(57) **CLAIM**

The ornamental design for a bottle holder, as shown and described.

DESCRIPTION

FIG. 1 is a perspective view of a bottle holder showing my new design;

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1; and,

FIG. 8 is a perspective view of the bottle holder shown in a folded configuration.

The broken lines show portions of the bottle holder and form no part of the claimed design.

1 Claim, 8 Drawing Sheets(56)
